LOCOMOTIVE STOKER

Original Filed Feb. 5, 1932

UNITED STATES PATENT OFFICE

1,993,305

LOCOMOTIVE STOKER

John W. Myers, Roanoke, Va., assignor to The Standard Stoker Company, Incorporated, a corporation of Delaware

Application February 5, 1932, Serial No. 591,128
Renewed January 14, 1935

5 Claims. (Cl. 198—15)

This invention relates to stokers for locomotives and more particularly to stokers of the type in which fuel is delivered from the tender to the firing opening in the locomotive boiler back-
5 head.

It is the main object of the invention to provide a novel stoker fuel conveying system which will conduct the fuel from a source of supply, as from a tender, to the firing opening in the back-
10 head of a locomotive in the most direct course consistent with permissible obstruction of space rearward of the backhead, and with a minimum of crushing or breaking down of the fuel.

It is a further object of the invention to pro-
15 vide a novel stoker fuel conveying system pecu-
liarly adaptable to locomotives of the deckless type, which comprises a fuel transfer conduit mounted on the tender, including a horizontal rearward section and an upwardly inclined for-
20 ward section, the junction between the sections being located rearward of the front wall of the tender, and a riser conduit flexibly connected at its lower end with the forward end of the transfer conduit and extending upwardly and
25 forwardly through the apron between the locomotive and tender to the firing opening.

A further object of the invention resides in the provision of a novel stoker trough having an open mouth portion, comprising a substan-
30 tially horizontal rearward section and an up-
wardly inclined forward section, the junction of the two sections being located within the open mouth portion of the trough.

The invention accordingly, comprises the fea-
35 tures of construction, combinations of elements and arrangement of parts hereinafter described and illustrated in the accompanying drawing in which

Fig. 1 is a longitudinal vertical central sec-
40 tion through a portion of a locomotive and its tender with a stoker partly in similar section and partly in side elevation applied thereto; and

Fig. 2 is a sectional view on the line 2—2 of Fig. 1.

45 In the drawing, the locomotive is designated generally by the numeral 10 and comprises the firebox 11 having grates 12, and a backwall 13 with a firing opening 14 therethrough. The ten-
50 der is represented by the numeral 15 having a fuel bin 16 with a coal gate 17, a floor or deck 18 having a longitudinal centrally located aper-
ture 19 normally closed by a plurality of slide-
55 able plates 20 which are arranged to be withdrawn from covering position to regulate the delivery of fuel from the fuel bin 16.

Movably mounted on the tender below the fuel bin 16 is a transfer conduit designated as a whole by the numeral 21 and which comprises the horizontal rearward conduit section or trough section 22 and the upwardly inclined forward conduit section 23. The upwardly inclined forward conduit section 23 includes a rearward open mouth portion 24 and a tubular forward portion 25. The junction of the horizontal conduit section 22 and the inclined conduit section 23 is located rearward of the front wall 26 of the tender and is preferably enlarged, as at 27. Viewed from another aspect, the transfer conduit 21 may be said to comprise the open mouth trough which includes the horizontal rearward portion or section 22 and the upwardly inclined portion or section 24, the tubular forward portion 25 forming a continuation of the inclined portion 23 and having its axis in coincidence with that of the inclined portion 23.

5 Conveyer screws 28 and 29 are mounted in the horizontal conduit section 22 and the inclined conduit section 23 respectively, and are universally connected by a joint 60 at the junction of the respective conduits within the enlarged portion 27. The conveyor screw 28 is driven from its rearward end through gearing (not shown) in the gear housing 30 in a manner so well known in the art as not to require particular description. A crusher 31, arching over the conveyor screw 29, is provided in the open mouth portion 24 of the inclined conduit section 23 and cooperates with the screw 29 to reduce the large lumps of fuel to a suitable size for firing.

Extending rearwardly from the backwall 13 of the locomotive is a support member 32, to which is hinged one end of the apron 33. The other end of the apron 33 rests on the tender deck 18, over which it is free to slide as relative movement between the tender and locomotive occurs. A curving riser conduit 34 extends generally upwardly and forwardly through an opening 35 in the apron 33 from a point therebelow to the lower portion of the firing opening 14. The conduit 34 is rigidly secured to the locomotive by suitable means, as by the flange 36 and brackets 37 and 38. The lower end of the conduit 34 is provided with a spherical split flange 39.

Slidably mounted on the forward end of the tubular portion 25 of the conduit section 23 and received in the spherical split flange 39 is a sleeve 40, the whole forming a ball joint 41 providing for universal and longitudinal movement between transfer conduit 21 and the riser conduit 34. To provide for vertical displacement of

the locomotive with respect to the tender and to further provide for relative movement between the locomotive and tender in going around curves, the conduit 21 is mounted to rotate or 5 pivot about a substantially vertical axis as well as to rock about a substantially horizontal transversely extending axis.

For this purpose a bracket 42 is rigidly secured to the conduit 21 between its forward and rearward ends. The lower portion of the bracket 42 10 comprises a horizontally and transversely extending member 43 received in the angle members 44. The angle members 44 which extend forwardly and downwardly for attachment to an adjacent 15 portion of the tender are supported adjacent the bracket 42 by substantially channel shaped members 45. The undersides of the end portions of the member 43 are preferably curved so that the bracket 42 and conduit may rock about a transversely extending horizontal axis.

Interposed between the horizontal portions 46 of the angle members 44 and the channel shaped members 45 is a transversely extending bar 47 which underlies and is adjacent to the member 43 20 of the bracket. The bar 47 and member 43 are provided with registering apertures for receiving a vertical pin 48 which, although it enables rotation or pivoting of the conduit 21 about a vertical axis, prevents longitudinal movement thereof. 25 The outer ends of the member 43 are also curved so that when the bracket 42 and conduit 21 rotate about the pivot pin 48 sufficient clearance will be provided between them and the angle members 44.

Since the conduit 21 is movably mounted on 30 the tender and therefore assumes various relative positions with respect to the opening 19, through which fuel is permitted to fall into the conduit 21, means is provided for preventing the escape of fuel between the sides of the conduit and the floor 35 of the fuel bin. This means comprises a ring member 49 surrounding the opening 19 and is movably supported on the underside of the floor by brackets 50. The ring member 49 is angularly shaped in cross section, being provided with a 40 vertical flange 51 extending downwardly within the conduit and a substantially horizontal flange 52 interposed between the supporting brackets 50 and the floor of the tender. The brackets 50 are so formed that sufficient space is provided to 45 permit the ring member 49 and conduit 21 to move with respect thereto as relative movement between the tender and conduit 21 occurs.

A fuel distributor plate 53, of any suitable design, extends forwardly from the upper marginal 55 edge of the bottom wall of the riser conduit 34 through the firing opening 14 into the firebox 11. Located at the rear of the distributor plate 53 is a pressure fluid distributor head 54 provided in its front face with a series of jet openings 55 60 through which pressure fluid, as steam, is ejected for impelling fuel over the distributor plate. Pressure fluid is admitted to the distributor head 54 through any suitable number of supply pipes 56.

65 While the invention has been described as applied to a locomotive of the deckless type it will be apparent that it may be used to advantage in stoker installations on other types of locomotives.

I claim:

70 1. In a locomotive provided with a firebox having a firing opening and a tender having a fuel bin, a fuel conduit system comprising a fuel transfer conduit mounted beneath the fuel bin including a horizontal open mouth rearward section and 75 an upwardly inclined forward section, said last

named section having a rearward open mouth portion and a tubular forward portion, the junction between said rearward and forward sections being located within the open mouth portion of said transfer conduit, a screw in said rearward section and a screw in said inclined forward section, the adjacent ends of said screws being flexibly connected within said open mouth portion and in the vicinity of the juncture between said sections, a crusher arching over the screw in said inclined forward section, said crusher being disposed within said open mouth portion and forward of the flexible connection between said screws, and a riser conduit flexibly connected at its lower end with the forward end of said transfer conduit and extending upwardly and forwardly therefrom to the lower portion of said firing opening.

2. In combination with a deckless locomotive provided with a firebox having a firing opening, 20 a tender and a movable apron between the locomotive and tender forming a movable deck for said locomotive, a fuel transfer conduit fixedly mounted on the tender with respect to longitudinal movement thereof and pivotally mounted on 25 the tender about transverse and vertical axes, said transfer conduit including a horizontal rearward section and an upwardly inclined forward section, the junction between said sections being disposed rearward of the front wall of the tender, 30 a screw in rearward section and a screw in said inclined section, the adjacent ends of said screws being flexibly connected within said open mouth portion and in the vicinity of the juncture between said sections, and a riser conduit fixed on 35 the locomotive flexibly and telescopically connected at its lower end with the forward end of said transfer conduit and extending upwardly and forwardly through said movable apron to the firing opening.

3. In combination with a deckless locomotive provided with a firebox having a firing opening, a tender and a movable apron between the locomotive and tender forming a movable deck for said locomotive, a stoker comprising a fuel transfer conduit fixedly mounted on the tender with 40 reference to longitudinal movement thereof and pivotally mounted intermediate its ends to swing about horizontal and transverse axes, said transfer conduit including a horizontal rearward section and an upwardly inclined forward section, the junction between said sections being disposed rearward of the front wall of the tender, a conveyor screw in each of said conduit sections for advancing fuel therethrough, said conveyor screws 45 being universally connected within the open mouth portion of said transfer conduit and in the vicinity of the juncture between said sections, and a riser conduit flexibly connected at its lower end with the forward end of said transfer conduit and extending upwardly and forwardly through said movable apron to the firing opening.

4. In combination with a deckless locomotive provided with a firebox having a firing opening, 55 a tender and a movable apron between the locomotive and tender forming a movable deck for said locomotive, a fuel transfer conduit fixedly mounted on the tender with respect to longitudinal movement thereof and pivotally mounted on the tender to swing about transverse and vertical axes, and a riser conduit flexibly connected at its lower end with the forward end of said transfer conduit and extending upwardly and forwardly through said movable apron to the firing opening.

5 10 15 20 25 30 35 40 45 50 55 60 65 70 75

5. In combination with a deckless locomotive provided with a firebox having a firing opening, a tender and a movable apron between the locomotive and tender forming a movable deck for said locomotive, a fuel transfer conduit fixedly mounted on the tender with respect to longitudinal movement thereof and pivotally mounted on

the tender to swing about transverse and vertical axes, and a riser conduit fixed on the locomotive flexibly and telescopically connected at its lower end with the forward end of said transfer conduit and extending upwardly and forwardly through said movable apron to the firing opening.
